UNITED STATES PATENT OFFICE

ROBERT E. WILLARD, OF MINNEAPOLIS, MINNESOTA, ASSIGNOR, BY MESNE ASSIGNMENTS, TO BRIQUET ENGINEERING COMPANY, OF MINNEAPOLIS, MINNESOTA, A CORPORATION OF DELAWARE

BINDER SPRAYER

Application filed April 28, 1930. Serial No. 447,925.

My present invention relates chiefly to an improved mixer for intimately commingling finely ground or pulverized solid materials with liquid substances and is directed particularly to the provision of an apparatus or device for effectually commingling pulverized coal with a suitable binder in the preparation thereof for the making of briquettes. This device is herein designated as a binder sprayer.

Generally stated, the invention consists of the novel devices, combinations of devices, and arrangement of parts hereinafter described and defined in the claims.

The briquette-forming material which may be finely ground or pulverized anthracite or bituminous coal or lignite should come from the customary or any suitable drier at a quite high temperature, say 400 F., having preferably a moisture content of approximately two per cent. Such briquetting material is fed to my improved mixer where it is commingled with a liquid binder of asphalt or asphalt compound and at the same time is subjected to the direct action of superheated steam and to the indirect action of a steam jacket.

A commercial form of the improved binder sprayer is illustrated in the accompanying drawings, wherein like characters indicate like parts throughout the several views.

Referring to the drawings:

Fig. 1 is an elevation showing the improved binder sprayer;

Fig. 2 is a vertical section taken on the line 2-2 of Fig. 1; and

Figs. 3, 4, 5, 6 and 7 are horizontal sections taken respectively on the lines 3-3, 4-4, 5-5, 6-6 and 7-7 of Fig. 2.

The device comprises an upright container preferably of cylindrical form, the cylinder being made up of two semi-cylindrical sections 8 and 9 connected at one side by hinges 10 and normally held together at their opposite sides by a suitable clamp 11. The shell section 8 at its lower end is fixed to the flanged anchoring ring 12 which, in turn is attached to the top plate 13 of a receiving device such as a fluxer, the latter having a large opening 14 aligned with the bottom of the cylindrical shell. A circular head 15 is secured to the

upper end of the fixed shell section 8. Rigidly secured to the lower end of the fixed shell section 8 and extending approximately diametrically across the shell is a bridge bar 16 provided at its center with a hub 17 that is aligned with a hub 18 on the head 15.

Located within a two-part cylindrical shell or container are conical baffles of which, as shown, there are three. The upper conical baffle 19, the intermediate conical baffle 20, and the lower conical baffle 21 are each made up of hollow approximately semi-circular sections that are rigidly secured to the respective shell sections 8 and 9 so that they come together as best shown in Fig. 6, when the shell section 9 is closed against the shell section 8. By reference particularly to Figs. 2 and 6, it will be noted that the semi-circular baffles are formed with steam chambers 22 that are tapped by steam supply pipes 23 and drain pipes 24. The pipes 23 may be coupled up to a source of steam supply by any suitable means although the connections to the nipples on the movable shell section should include flexible or jointed hose or pipe sections.

Extended axially through the shell is an upright hollow shaft 25. This shaft is journaled in the axially aligned hubs 17 and 18 and at its upper end, as shown, is provided with a pulley 26 whereby it may be rotated at quite high speed. Secured to the shaft 25, just below the upper baffle 19, is an impeller head 27 that projects outward under the contracted portion of the upper baffle 19; and secured to said shaft below the baffles 20 and 21 are impeller heads 28 and 29 that project outward, respectively, under the said conical baffles 20 and 21. The upper impeller head 27 is formed with peripheral notches 27^a and the lower impeller heads 28 and 29 are formed with notches or grooves 28^a and 29^a, respectively. The purpose of these notches is to give the rotating impeller heads a better grip on material delivered thereto, as will presently be noted and in effect, the said heads are fluted impeller heads. The impeller head 27 is formed with radial binder-delivery ducts 30 that extend from the interior of the hollow shaft 25 into

the pockets 27^a; and just below these ducts the shaft 25 is provided with a plug 25^a.

The binder material will be delivered into the upper end of the hollow shaft 25 and under the action of gravity, due to head of the supply, and to centrifugal force, will be discharged through the ducts 30. For the introduction of the pulverized coal or briquette-forming material into the container, 10 the shell section 8, near its upper end is provided with a large inlet passage 31 best shown in Fig. 2. Directly below the inlet opening 31 are several, as shown two, steam jets 32, that are directed obliquely downward 15 and in the direction of the rotation of the shaft 25 and its impeller heads. These steam jets will preferably be connected to a source of super-heated steam.

The pulverized coal or briquette material 20 will be delivered into the upper portion of the shell or casing at quite high temperature preferably at a temperature already stated of about 400 degrees F. The binder which will usually be asphalt or asphalt compound 25 will be delivered into the upper end of the shaft 25 at a temperature of say approximately 175 degrees F. The pulverized briquette material entering the casing through the opening 31 will be immediately 30 subjected to the super-heated steam blasts from the jets 32 and by the jet action alone will be given a whirling motion against the upper baffle 19 and from the baffle will be delivered onto the impeller head 27 and this 35 head, rotating at high speed, will throw the briquette material radially outward in a spray or loose condition against the oblique under surface of the upper baffle; and at the same time the fluid binder will be thrown in 40 a fine spray into the shower or spray of briquette material and will cause a very thorough commingling of the binder with the coal or briquette material. The coal or briquette material supplied with the proper 45 amount of binder and quite thoroughly commingled by the action just described will, by the intermediate baffle 20, be poured downward into the intermediate impeller head 28 and by the latter again thrown outward against the oblique under surface of the baffle 20 and from thence by the baffle 21, the briquette material will be delivered to the lower impeller head 29. Thus the binder is 50 supplied to the briquette material and very 55 thoroughly and evenly commingled therewith.

This binder sprayer will be found efficient for many purposes but has been especially designed for use as part of a briquette-forming apparatus used for carrying out an improved process of forming briquettes disclosed and claimed in the companion application filed of even date herewith under Serial Number 447,926.

55 The steam jets 32 in the arrangement de-

scribed, perform two functions, to wit: they set up a whirling motion of the briquette material as it enters the sprayer and they maintain or keep up the temperature thereof or even increase the temperature thereof so 70 that the coal or briquette particles will be not only very thoroughly commingled with the binder but will quickly absorb the same. In some instances, hot air instead of steam might be supplied to the jets 32. The briquette material is further kept in hot condition while passing through the binder sprayer by the steam heated walls of the baffles against which the material is repeatedly projected. 80

The main purpose of making the casing of the sprayer in two sections is to permit the same to be opened up to clean out or repair the interior of the same and hence it will be understood that this, as well as certain other 85 features, while important, may in some instances be omitted without departing from the spirit of the invention herein disclosed and claimed.

What I claim is:

1. A sprayer of the kind described comprising an upright casing provided within with a conical baffle having beveled upper and lower surfaces, a rotary shaft extending axially through said casing and provided with an impeller head located below the upper inclined portion of said baffle and arranged to throw the briquette material against the inclined under surface of said baffle, and means for the delivery of steam or hot air into the 100 upper portion of said casing in a direction to cause the briquette material to take up a whirling motion above and against said baffle. 90

2. A sprayer of the kind described comprising an upright casing provided within with a conical baffle having beveled upper and lower surfaces, a rotary shaft extending axially through said casing and provided with an impeller head located below the upper inclined portion of said baffle and arranged to throw the briquette material against the inclined under surface of said baffle, said shaft and head having binder-delivery passages arranged to project the spray of binding material into the briquette material thrown from said impeller head, and means for the delivery of steam or hot air into the upper portion of said casing in a direction to cause the briquette material to take up a whirling motion above and against said baffle. 105

3. A sprayer of the kind described comprising an upright casing provided within with a conical baffle having beveled upper and lower surfaces, and a rotary shaft extending axially through said casing and provided with an impeller head located below the upper inclined portion of said baffle and arranged to throw the briquette material 110 120 125 130

against the inclined under surface of said baffle, said baffle being hollow and combined with means for supplying steam thereto.

4. A sprayer of the kind described comprising an upright casing provided within with a conical baffle having beveled upper and lower surfaces, and a rotary shaft extending axially through said casing and provided with an impeller head located below the upper inclined portion of said baffle and arranged to throw the briquette material against the inclined under surface of said baffle, said shell and said baffle being made up of separable sections permitting the apparatus to be opened up for inspection, cleaning or repair.

5. A sprayer of the kind described comprising an upright drum-like casing provided within with baffles located one above the other, a hollow shaft axially journaled in said casing and provided with upper and lower impeller heads located below and adapted to receive briquette material from the respective baffles, said upper impeller head having out-leading binder-delivery ducts receiving the binder material from the interior of said shaft and arranged to project a spray of binder material into the briquette material delivered from said upper head.

6. The structure defined in claim 5 in which said casing is made up of two sections hingedly connected and to said baffles are made up of sections secured to the respective case sections.

7. The structure defined in claim 5 in further combination with steam jets opening into said casing above the upper baffle and arranged to set up a whirling motion of the briquette material delivered into said casing.

In testimony whereof I affix my signature.
ROBERT E. WILLARD.
